(57) **CLAIM**

The ornamental design for a hydration reservoir, as shown and described.

DESCRIPTION

FIG. 1 is a top front isometric view of the new design;
FIG. 2 is a bottom rear isometric view thereof;
FIG. 3 is a front plan view thereof;
FIG. 4 is a rear plan view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a detailed view of FIG. 2;
FIG. 10 is a detailed view of FIG. 4; and,
FIG. 11 is a detailed view of FIG. 7, with the corresponding structure on the opposite side of the design being the mirror image thereof.

The dashed lines shown in the drawings illustrate portions of the hydration reservoir that form no part of the claimed design.

1 Claim, 9 Drawing Sheets
